TEXTILE FABRIC OR THE LIKE

Annabelle P. Crotty, Arlington, Va.

Application August 25, 1950, Serial No. 11,934

Term of patent 7 years

(Cl. D92—1)

To all whom it may concern:

Be it known that I, Annabelle P. Crotty, a citizen of the United States, a resident of Arlington, Virginia, have invented a new, original, and ornamental Design for a Textile Fabric or the like, of which the following is a specification, reference being had to the accompanying drawing, forming part thereof.

The figure is a plan view of a textile fabric showing my new design. The design unit is outlined by broken lines and is repeated over the textile fabric as indicated.

I claim:

The ornamental design for a textile fabric or the like, substantially as shown and described.

ANNABELLE P. CROTTY.
